UNITED STATES PATENT OFFICE.

MISSOURI A. NARMORE, OF FORT WORTH, TEXAS.

BUTTONLESS NECKBAND.

1,267,261.

Specification of Letters Patent.

Patented May 21, 1918.

Application filed June 2, 1917. Serial No. 172,412.

To all whom it may concern:

Be it known that I, MISSOURI A. NARMORE, a citizen of the United States, residing at Fort Worth, in the county of Tarrant and State of Texas, have invented certain useful Improvements in Buttonless Neckbands, of which the following is a specification, reference being had therein to the accompanying drawing.

10 The present invention has reference generally to improvements in that class of inventions known as apparel and more particularly relates to a buttonless neck band.

This invention has for its principal aim 15 and object to provide a device of the above character designed so as to be removably fastened about the neck of the wearer without the employment of a collar button to hold the ends in engagement with each other, thus obviating the employment of collar buttons which would have a tendency to discolor the neck of the wearer.

As an additional object, this invention embraces the provision of a shirt band, the 25 construction of which is such that the ends may be secured by a collar button if so desired to enable an effective attachment of a collar of the usual type.

More particularly, this invention embraces the provision of improved means on the shirt band for removably anchoring a collar of a special construction thereto without the employment of a collar button.

Among the other aims and objects of this 35 invention may be recited the provision of a device of the character described with a view to compactness, and in which the number of parts are few, the construction simple, the cost of production low and the efficiency high.

Other objects as well as the nature, characteristic features and scope of this invention will be more readily apparent from the following description taken in connection 45 with the accompanying drawings and pointed out in the claims forming a part of this specification.

The invention is clearly illustrated in the accompanying drawings, in which:

50 Figure 1 is a perspective view of the improved shirt band in an open position;

Fig. 2 is a fragmentary perspective detail showing the neck band in a closed position;

55 Fig. 3 is a fragmentary top plan showing

the relation of the parts when in a closed position;

Fig. 4 is a fragmentary perspective detail looking toward the rear of the neck band.

Similar characters of reference are employed in all of the above described views to indicate corresponding parts.

Referring now, more particularly, to the accompanying drawings there is provided a shirt 1 to the upper edge of which is secured the body of an improved neck band indicated in its entirety by the numeral 2, one end thereof extending beyond the adjacent edge 3 of the open front of the shirt 70 and constitutes a supporting flap 4. The neck band adjacent the flap 4 is provided with a downwardly extending slot 5 from the upper edge and which terminates in an opening 6 approximately intermediate the 75 upper and lower edges for a purpose that will presently appear. The other end portion of the neck band has secured to its inner surface adjacent its outer end through the instrumentality of stitches 7 the inner 80 edge of an extension 8 which projects from the adjacent upper edge of the shirt 1 and constitutes a protection flap in a manner that will hereinafter become apparent. That portion of the neck band between the 85 stitches 7 and the outer end constitutes a tongue 9 which is provided on its under edge with an upwardly extending slot 10 terminating in an opening 11 approximately intermediate the upper and lower 90 edges thereof and which is designed for removable interlocking engagement with the slot 5 for fastening the ends of the neck band together in the manner indicated in Fig. 2. If it is desired to use a collar button, not shown, the same is adapted to be engaged through the opening 11 so that its base will abut the flap 8, and said button is also adapted to be engaged by the opening 6 adjacent the other end of the neck band.

95 In order to facilitate the attachment of a specially constructed collar to the improved neck band without employing a collar button, a tab is secured to the outer surface of the neck band in substantial alinement with the outer edge of the slot 5 through the medium of suitable stitches 13. Extending upwardly from the lower edge of the flap 12 is a slot 14 which terminates in an opening 15 providing a substantial tongue 16 on the 110

outer portion of the flap 12. This tongue is adapted for interlocking engagement with the correspondingly shaped flap of a collar, not shown, such as the collar described and 5 claimed in my co-pending application bearing Serial No. 172,411, filed June 2, 1917.

For the purpose of fastening the collar to the rear of the neck band another tab 17 is connected, through the instrumentality of 10 stitches 18, to the outer surface of the band approximately intermediate the ends thereof and is provided from its under edge with an upwardly extending slot 19 which terminates in an opening 20, said slot forming a 15 tongue 21 on the outer end of the tab. This tab is adapted for engagement with a complementary tab on a specially constructed collar or if it is desired to use a conventional type of collar on the neck band, it is only 20 necessary to insert a collar button, not shown, through the opening 20.

It is believed in view of the foregoing description that a further detailed description of the operation of the invention is entirely 25 unnecessary. Likewise it is believed that the advantages of the invention will be readily apparent.

It will be understood that the above description and accompanying drawings comprehend only the general and preferred embodiment of this invention and that various minor changes in detail of construction, proportion and arrangement of the parts may 30 be made within the scope of the appended 35 claims and without sacrificing any of the advantages of this invention.

Having thus fully described this invention, what is claimed as new and desired to be secured by Letters-Patent, is:—

40. 1. A neck band for shirts including a body, a flap projecting from one end thereof,

the body being provided with a slot extending downwardly from its upper edge at a point adjacent the inner end of the flap, the opposite end of the body being provided 45 with a slot extending upwardly from its lower edge and forming a tongue for interlocking engagement with the first mentioned slot, and slotted tabs carried by the rear surface of the body and the outer surface of 50 55 the flap.

2. A neck band for shirts having open fronts including a body carried by the upper edge of the shirt, one end of the body continuing beyond the adjacent edge of the 60 open front of the shirt and forming a flap, the body being provided adjacent the inner end of the flap with a slot extending downwardly from its upper edge, said slot terminating in an opening, the opposite end of the 65 body being provided adjacent its free end with a slot which extends upwardly from the lower edge and terminates in an opening, said slot forming a tongue on the outer end of the body designed for interlocking engagement with the slot adjacent the flap, and slotted collar engaging tabs carried by the outer surface of the band intermediate the ends thereof and by the outer surface 70 of the flap.

3. A neck band for shirts including a body, a flap formed on one end of the body, the respective ends of the body being formed with slots designed for interlocking engagement with each other and being also designed to accommodate a collar button if desired, and slotted collar engaging tabs carried by the outer surface of the body and the outer surface of the flap.

In testimony whereof I affix my signature. 80

MISSOURI A. NARMORE.
